ATTACHED KNITTING NEEDLE

James H. Graham, Torrington, Conn.

Application May 15, 1933, Serial No. 671,123

1 Claim. (Cl. 66—117)

This invention relates to hand knitting needles, and more particularly to an elongated needle having two cylindrical knitting points connected together by a single flexible central strand.

One object of this invention is to provide a knitting needle of the above nature in which the central connecting strand is made from flexible wire of smaller diameter than the end points.

A further object is to provide a knitting needle of the above nature in which the joints between the central strand and the knitting points are smoothly tapered and are of a very strong durable construction.

A further object is to provide a "duplex" knitting needle of the above nature which will be simple in construction, inexpensive to manufacture, easy to manipulate, compact, ornamental in appearance, and very efficient in use.

With these and other objects in view there have been illustrated on the accompanying drawing several forms in which the invention may be conveniently embodied in practice.

In the drawing:

Fig. 1 is a perspective view of the duplex knitting needle as it appears when in position for use.

Fig. 2 is a longitudinal side view of one of the knitting points and central connecting strand.

Fig. 3 is an enlarged fragmentary sectional exploded view of the same showing the construction of the joint between the central strand and the knitting point.

Fig. 4 is a view similar to Fig. 3 showing the parts in assembled position.

Fig. 5 is a fragmentary view of a modified form of the invention.

Fig. 6 is a fragmentary view of another modified form in which the knitting point is united to the central strand by "butt-welding".

Fig. 7 shows a further modified form of needle having a composition point molded upon the ends of the central strand.

In the use of previous forms of duplex knitting needles, considerable difficulty has been experienced due to breakage at the joints between the knitting points and the central strand caused by the repeated bending strains to which said joints were subjected. The material being knitted was also quite apt to catch on the abrupt shoulders at said joints when "knitting-off" from one needle on to the other. By means of the present invention, the above and other disadvantages have been eliminated.

Referring now to the drawing in which like

reference numerals denote corresponding parts throughout the several views, the numerals 10 and 11 indicate respectively a pair of knitting points which are substantially cylindrical in shape and have their outer extremities 12 and 13 made conical in the usual manner. The inner ends 14 and 15 of said points are tapered and are rigidly secured to a long slender flexible connecting strand 16, preferably of wire. The points 10 and 11 are shown in Figs. 3 and 4 as 10 being tapped at 17 to receive the threaded ends 18 of the central strand, whereby the points 10 and 11 may be readily screwed upon the threaded ends 18 of the wire strand 16.

After the parts have been assembled, the joint 18 may be squeezed inwardly at a plurality of spaced points 18a adjacent the open end of said tapped portion, as indicated by the dotted lines in Fig. 4, to deform the metal of both said point and said strand. All possibility of relative twisting or 20 sliding of said parts will thus be avoided when grinding or otherwise smoothing the joint.

In order to form abutments for the inner tapered ends 14 and 15 of the knitting points 10 and 11, the central strand is provided with a 25 pair of integral frusto-conical sections 20, preferably formed in a heading machine. The enlarged outer ends of the conical sections 20 are adapted to lie in contact with the annular ends 19 of the points 10 and 11 when the parts are 30 in the assembled relation shown in Fig. 4.

The inner ends 14 and 15 of the knitting points are adapted to lie flush with the edge of the conical sections 20, and when assembled, the joints may be burnished, spun, or otherwise 35 smoothed off.

As noted in Fig. 3, a fin 22 is formed at the large end of each conical section 20 during the heading operation. This fin is preferably removed after the parts have been assembled. 40

In the modified form of the invention shown in Fig. 5, the relatively large knitting point 23 of the needle is formed as an integral part of the central wire connecting strand 24. In this construction, the central strand is originally of the 45 same diameter as the end knitting points and may be reduced to a smaller diameter, as shown, by rolling, drawing, or swaging, etc.

In the modified form shown in Fig. 6, the "duplex" knitting needle comprises a flexible central wire strand 26 of small diameter, and having an enlarged head 27 butt-welded at 28 to the knitting point 25.

A still further modified form is shown in Fig. 7, in which case the knitting points 28 are made 55

of composition molded or otherwise consolidated around the end 29 of the flexible connecting strand 30, which end is preferably roughened, as by knurling. If desired, the central strand 5 30 may be provided with headed conical sections 31 to form shoulders for engagement by the inner ends of the molded material of the point 28.

While there have been disclosed in this specification several forms in which the invention may 10 be embodied, it is to be understood that these forms are shown for the purpose of illustration only, and that the invention is not to be limited to the specific disclosures but may be modified and embodied in various other forms without departing from its spirit. In short, the invention

includes all the modifications and embodiments coming within the scope of the following claim.

Having thus fully described the invention what is claimed as new and for which it is desired to secure Letters Patent is:

In a knitting needle, a pair of relatively large metal knitting sections having pointed outer ends, and a relatively small flexible metal central strand butt-welded to the inner ends of said knitting sections, the ends of said strand having 10 enlarged tapered sections, and the inner ends of said knitting sections being reduced to substantially the same diameter as said enlarged tapered sections at the welded joints.
